UNITED STATES PATENT OFFICE.

GEORGE SYDENHAM CLARKE, OF LONDON, ENGLAND, ASSIGNOR TO EDMUND L. ZALINSKI, OF THE UNITED STATES ARMY.

FIELD-GUN CARRIAGE.

SPECIFICATION forming part of Letters Patent No. 686,713, dated November 19, 1901.

Application filed January 25, 1901. Renewed September 21, 1901. Serial No. 76,089. (No model.)

To all whom it may concern:

Be it known that I, GEORGE SYDENHAM CLARKE, residing at London, England, have invented certain new and useful Improvements in Field-Gun Carriages, of which the following is a specification, reference being had therein to the accompanying drawings.

This invention relates to carriages for field-guns.

10 The object of the invention is to provide a field-gun carriage with an anchor or spade to resist recoil, which spade shall permit a free traverse or swing of the gun-carriage without detachment and which will permit recoil and return the carriage to firing position after recoil.

Figure 1 is a section of a gun-carriage with anchor mechanism attached and shown in elevation, some other parts being also shown in elevation. Fig. 2 is a section of carriage and anchor mechanism. Fig. 3 is an elevation of spade and cylinders detached. Fig. 4 is a detail section of sleeve and elevation of lever for holding up spade. Fig. 5 is a broken section showing connection of lever to trail.

The numeral 1 indicates the axle of a gun-carriage, 2 a wheel, and 3 the trail of a field-gun carriage, which may be of any usual construction. As shown, the trail is a metallic shell. A bracket 4 is forged or otherwise rigidly connected to the axle at the center thereof and directly under the gun, and to this bracket a hollow cylinder 5 is connected by a pivot, the bracket and the end of the cylinder thus being connected, so that the cylinder 5 may swing as a pendulum lengthwise of the gun. A second and smaller cylinder 6 telescopes within the cylinder 5, being free both to turn and slide therein, but being prevented from withdrawal by any suitable mechanism, as by the attachment of the spring 7 to both sections of the cylinder. A coiled spring 7 within the two cylinders tends to project the smaller cylinder. The strength of this spring is such that it will not quite sustain the weight of the gun and carriage, but will press the smaller cylinder outward with a force just less than enough to sustain such weight. The smaller cylinder 6 has a broad spade 8 attached thereto and preferably provided with a serrated end. The

length of the cylinders is such as to force the spade well into the ground when the axle is directly over the spade and to secure a good engagement of the spade when the gun is forward, as in Figs. 1 and 2. The cylinder 5 has a hook or socket 9, connected to a ring or otherwise attached. The trail has a sleeve or bar 10, extending crosswise and provided with a hook 11, which may engage hook 9 on the cylinder when the said cylinder is swung up against the trail, (dotted lines, Fig. 1,) and this sleeve or bar may be rocked by lever 12, so as to bring hook 11 into engagement with hook 9 and hold the cylinder and spade in upward position. Lever 12 may be held against the trail by a pin 13, passing through a hole in the lever and into a hole in the trail, or other means for holding the lever in locked position may be employed. The spade or its handle, which is cylinder 6, is connected to a strong spring 15 by a cable or cables 16, attached to the spade and to the spring or to a guide-rod 18 within the spring. A casing 19, firmly secured to the trail, incloses the spring 15, and the spring bears against the end of said cylinder when compressed.

Any of the usual mechanisms for regulating the tension of the springs may be employed, such mechanism being common in several of the mechanic arts.

The gun being in firing position, as in Fig. 1, will on firing be driven back by the recoil, forcing the spade more firmly into the ground and by the cable 16 compressing the spring 15. As soon as the recoil has exhausted itself (and the usual wheel-brakes may assist in checking the recoil) the spring 15, drawing on the cable 16 and spade 8, forces the gun and carriage forward, and so the gun is automatically returned to firing position after each discharge.

As the spade handle or cylinder 6 is free to turn in the cylinder 5, the carriage may be swung about the spade to a considerable extent without removing the spade from the ground. This is an important advantage over usual constructions.

The drawings do not purport to give exact constructions and proportions, but only the essential elements, which are in actual construction varied according to the gun-carriage

construction and the requirements of usage. The claims indicate the scope of what I believe my invention to embrace.

What I claim is—

- 5 1. The combination with a field-gun carriage, of a spade-anchor hinged to the axle, and having a telescopic extension to the stem thereof.
- 10 2. The combination with the axle of a field-gun carriage, of a cylinder hinged thereto, a second cylinder within the first, extensible and rotatable therein, a spade-anchor connected to the second cylinder, and means for projecting the second cylinder.
- 15 3. The combination with a field-gun carriage, of a cylinder hinged to the axle thereof, a spring inclosed within the cylinder, a spade-anchor extensibly supported by the spring and rotatable with relation to the cylinder, and means connecting the spade to the trail of the gun.
- 20 4. The combination with the axle of a gun-carriage, of a spade-anchor having its support hinged to the axle and rotatable rela-

tively thereto, a spring connected to the trail, 25 and a flexible connection from said spring to the spade, whereby the spring is compressed as the carriage recoils, substantially as described.

5. In combination with a gun-carriage, a 30 spade-anchor extensibly propelled by a spring from said axle, and capable of swivel movement relatively thereto, a spring attached to the trail, and a flexible connection from the spade to the trail-or recoil-spring, substantially as described.

6. In combination with the axle of a gun-carriage, a cylinder hinged thereto and provided with an extensible spade, and a lever-catch on the trail by which the cylinder and 40 spade may be held up, substantially as described.

In testimony whereof I affix my signature in presence of two witnesses.

GEORGE SYDENHAM CLARKE.
